TRANSMISSION OF MESSAGES OR PICTURES OVER LONG DISTANCE LINES

Jacobo J. Laub, Breslau, and Friedrich Kirschstein, Berlin-Tempelhof, Germany, assignors to Radio Patents Corporation, New York, N. Y.

Application July 31, 1933, Serial No. 682,922
In Germany July 30, 1932

35 Claims. (Cl. 178—44)

(Granted under the provisions of sec. 14, act of
March 2, 1927; 357 O. G. 5)

It is well known to use high-frequency carrier waves upon which low-frequency or other currents representative of intelligence to be transmitted are modulated directly or by the use of intermediate frequencies, for so-called wired wireless transmission from point to point along telephone or telegraph wire lines. The original audio or other current modulated upon the carrier at one point is then demodulated from the carrier 5 wave by means of a detecting receiver at another point. By using a number of carrier waves having sufficiently different frequencies, a corresponding number of telephone conversations or other communications can be carried on and transmitted, 10 respectively, simultaneously over one line.

The carrier waves generally are greatly weakened (damped) while proceeding along the line. It has hitherto been believed that such weakening or attenuation of the carriers increases with 15 increasing frequencies. For this reason carrier wave frequencies below 40 kilocycles per second or, what means the same, of more than 7,500 meters in length, have only been used in practice. Higher carrier frequencies, i. e. shorter carrier 20 waves, have not been used because their damping, or attenuation, by aperiodical long-distance telephone circuits and lines was considered to be so excessive that no considerable distances could be bridged over by them. It was also believed 25 that the use of such short waves in wired wireless transmission is accompanied by an undesired lateral radiation of energy in the form of electromagnetic waves proceeding transversely from the lines, thereby destroying secrecy of the signals 30 and messages going to be transmitted.

The limitation of the carrier frequency range to below 40 kilocycles had the effect that only a 35 small number e. g. of conversations could be carried on simultaneously over one line (about 4 at the utmost) from one point to another one, and that the different conversations could be separated at the receiving points of the lines only with great difficulty and by means of extremely large and accordingly expensive filter chains. In 40 addition hereto, the disturbance (or noise) level within that frequency range has been proven to be very great in practice, especially on open-air lines so that hitherto one expected only a comparatively low amplification of the incoming carrier 45 wave current.

Extensive investigations of the inventors 50 showed the surprising result that carrier waves within the range of about 85 to 10,000, and more, kilocycles per second can be used and are of particular and extreme advantage in comparison 55 with far lower carrier wave frequencies hitherto used. This applies not only to lines comprising aperiodical open-air lines, but also to cable lines (trunk lines) comprising aperiodical non-concen- 60 trical conductors.

The reasons for that phenomenon as investigated and established by the inventors are, among others, the following:

It was first found that, contrary to common expectation, no essential losses of energy or power 5 caused by electro-magnetic radiation from the lines take place if carrier frequencies from about 85 to about 10,000, and more, kilocycles are used. For instance, at a distance of 100 meters laterally from an open-wire line along which a modulated carrier wave of 40 meters' length (7500 kilocycles) and of a few watts' energy has been transmitted, no messages modulated upon that carrier could be picked up even with most sensitive receivers. Consequently, by the use of carrier wave frequencies within the range of the 10 invention practical secrecy of all intelligence transmitted thereon is secured.

Very surprisingly it was also found that the damping, or attenuation, of carrier waves transmitted over a given distance does not increase 15 with their frequency in the high ranges, concerned by this invention, in the way as was hitherto generally believed. The inventors seek an explanation of this fact therein that the damping of 20 those waves is merely due to the so-called copper losses in the wires and not substantially to radiation losses, the latter being found much less than 25 expected.

Equally surprising it was found that the disturbance or noise level of the line decreases rapidly 30 with increasing frequency of the carrier wave so that the degree of amplification of the receiving circuit or circuits can be easily increased, and this to a greater extent than in the case of 35 carrier waves of the range hitherto used.

While a damping, or attenuation, equivalent to 4 Neper at the carrier frequency heretofore used 40 was so far assumed to be the highest admissible one between two points of a line, according to the invention and obviously due to its surprising findings outlined above, dampings or attenuations e. g. up to 10 to 12 Neper on open-wire lines at the frequency used, and in case of cables and trunks even up to 15 Neper and more, could be 45 safely overcome by using the high-frequency range suggested by the invention.

In other words, by means of the invention far greater distances between a transmitting and a receiving point can be bridged over than heretofore. 50

This may be explained by reference to the drawing which shows, in a diagrammatical way only, in Fig. 1 as ordinates the values of the losses of energy (level of damping or attenuation), if transmitted over aperiodical open-air lines, per unit of length of the line and the course of the disturbance (noise) level, both on the same scale and dependent upon the carrier wave frequencies which are shown as abscissae. As it 55 60

is understood, the signal level is derived from the losses of power level by subtracting the values of the latter from the transmitted energy. Fig. 2 shows diagrammatically a system for use of carrier frequencies within the range of our invention upon which currents representative of messages or other intelligence are modulated.

As Fig. 1 clearly shows, the values of the damping (or attenuation) increase with the carrier frequencies whereas the values of the disturbance simultaneously decrease with those frequencies so that a higher amplification can be used at the receiving point and thereby just as large, and even larger transmission distances can be bridged over than it was possible with the lower carrier wave range hitherto used. By way of example it may be mentioned that by means of waves within the frequency range according to the invention, and with a transmitter output energy of a few watts distances of 300 to 380 miles causing an attenuation of e. g. 10 to 12 Neper at the carrier frequency, can still be served over substantially aperiodical open-air lines comprising wires of a diameter of 4 millimeters, without applying any intermediate amplification, and if cables with substantially aperiodical non-concentrical conductors are used, distances up to 30 miles and more, causing a still higher attenuation than 10 to 12 Neper at the carrier frequency, can be safely bridged over in the same way.

The use of carrier waves having a high frequency range in accordance with the present invention offers, among others, the following fundamental advantages in comparison with the lower ranges hitherto used in practice. The number of talks and other communications to be carried on and transmitted simultaneously over one line is practically unlimited. For the purpose of separating the different talks on modulated carriers at a receiving point simple selective amplifier circuits as provided in ordinary broadcast receiving sets can be used. Owing to their high frequency, the carrier wave currents enter but slightly into the surface of copper wires. Consequently, conductors of the type having a thin copper coating on a wire, or support, of other material such as iron or steel can be used as well as solid copper conductors. Thereby the price of carrier lines can be considerably reduced. The transmission and receiving circuits and equipments can be of the type as normally manufactured in the broadcast industry. Consequently, they are so low in price that their use is also economical in case of transmission of intelligence, including pictures, over short distances where as it is well known equipments for long-wave service are very expensive and their use is therefore not lucrative. Transmission and receiving equipments for use with our invention are in general easily portable and can therefore be used in various special services such as telephone in trains, military or police purposes, etc. By means of high-frequency amplifiers tuned to the carrier waves by means of oscillatory circuits, a highly effective intermediate amplification can be ensured so that the total transmission distance obtainable is practically unlimited.

If in a multiple transmission of intelligence a number of communications are transmitted at the same time over the same line by means of modulated carrier waves of different high frequencies within the range of the present invention each of these carrier waves represents a so-called individual channel through which the

communication is transmitted. These simultaneously transmitted individual channels or modulated carrier waves can easily be separated at the receiver station by means of selective tuned amplifier circuits, the receiver station may be an intermediate one or an end station. If, particularly in such multiple transmission of intelligence, local weaknesses occur in the reception of one or some of the individual channels such weaknesses can be easily removed either by slight alteration of the carrier frequency of the respective channel or by tuning of the receiving amplifier circuit.

The diagrammatical exemplification of a system carrying into effect our invention, as shown in Fig. 2, consists of a transmission set using three-electrode tubes in known electrical arrangement to generate high frequency carrier oscillations upon which are modulated influencing currents representative of intelligence and of any frequency, from low frequency up to a frequency as high as e. g. currents which reproduce pictures, i. e. of the television range. The thus modulated carrier waves having a frequency within the range of the invention are transmitted over non-concentrical and spaced apart wires indicated in the drawing by dotted lines representative of such cable or open-wire lines, or of a combination thereof. Obviously this line is aperiodical, i. e. not tuned to the particular frequency of the carrier wave used. The receiving set may be an ordinary broadcasting receiver comprising a selective tunable amplifier circuit coupled by condensers with the line. But there may also be used in such a receiver set a special connection as shown by established symbols in Fig. 2 which do not need any further explanation.

Without limiting the broad scope of the invention as covered by the appended claims, we want to illustrate by way of example the nature of our invention in that it comprises the transmission of intelligence including messages, signals and pictures (television) along substantially aperiodical open-air lines over great distances, such as 100 miles, 125 miles and more, up to about 300 and 400 miles and more, using carrier waves including frequencies of 120 kilocycles up to about 10,000 kilocycles, and more, should a signal energy of e. g. about 3 watts be used. In case greater distances, causing correspondingly higher attenuations, are to be bridged over, an intermediate amplification may be suitably provided for by using an amplifier with selective input circuit tuned to the carrier wave and coupled to the lines e. g. by suitable condensers. Should our invention be used in connection with substantially aperiodical cables or trunks, distances up to 30 miles and more can easily be served using carrier wave frequencies of 85 kilocycles and more, including up to about 3000 kilocycles, and operating with a signal energy of e. g. about 3 watts. In every such case the input circuit of the amplifier at the receiving point simply has to be tuned to the carrier wave frequency which is to be received thereby.

It is to be understood that the invention is not limited to any exemplification given hereinbefore, but is to be derived in its broadest aspect from the appended claims.

What is claimed is:

1. A method of transmitting signals and communications of low frequencies up to high frequencies including the television range along aperiodical communication lines of the type comprising non-concentrical conductors with modu-

lated carrier frequencies in the range of and above 85 kilocycles over distances corresponding to an attenuation of about 4 or more Neper at the carrier frequency used.

5 2. A method of transmitting signals and communications of low frequencies up to high frequencies including the television range along aperiodical communication lines of the type comprising spaced apart non-concentrical conductors with modulated carrier frequencies in the range of and above 85 kilocycles over distances corresponding to an attenuation of about 4 or more Neper at the carrier frequency used.

10 3. A method of transmitting signals and communications of low frequencies up to high frequencies including the television range along communication lines of the type as ordinarily used for telephone and telegraph communication and comprising aperiodical spaced apart non-concentrical conductors, with modulated carrier frequencies in the range of and above 85 kilocycles over distances corresponding to an attenuation of about 4 or more Neper at the carrier frequency used.

15 4. A method of transmitting intelligence of low frequencies up to high frequencies including the television range along communication lines comprising aperiodical open-wire lines with modulated carrier frequencies in the range of and above 85 kilocycles over distances corresponding to an attenuation of about 4 or more Neper at the carrier frequency used.

20 5. A method of transmitting intelligence of low frequencies up to high frequencies including the television range along communication lines comprising aperiodical spaced apart non-concentrical cable lines with modulated carrier frequencies in the range of and above 85 kilocycles over distances corresponding to an attenuation of about 4 or more Neper at the carrier frequency used.

25 6. In a method of wired wireless transmission of intelligence of low frequencies up to high frequencies including the television range from point to point employing selective amplifier circuits at the receiving point; the transmission of modulated carrier waves over wires comprising aperiodical wires within the high frequency range above and including about 85 kilocycles and over distances where the signal level substantially surpasses the noise level.

30 7. A method of multiple transmission of intelligence of low frequencies up to high frequencies including the television range along communication lines with modulated carrier frequencies forming individual channels over distances corresponding to an attenuation of about 4 or more Neper at a carrier frequency used, said lines substantially comprising aperiodical open-wire lines, selecting said carrier frequencies within a range of about 85 to about 10,000 kilocycles, and separating the individual channels by tuned amplifier circuits at the receiver station.

35 8. A method of multiple transmission of intelligence of low frequencies up to high frequencies including the television range along communication lines with modulated carrier frequencies forming individual channels over distances corresponding to an attenuation of about 4 or more Neper at a carrier frequency used, said lines substantially comprising aperiodical spaced apart non-concentrical cable lines, selecting said carrier frequencies within a range of about 85 to about 10,000 kilocycles, and separating the in-

dividual channels by tuned amplifier circuits at the receiver station.

9. A method of multiple transmission of intelligence of low frequencies up to high frequencies including the television range along communication lines with modulated carrier frequencies forming individual channels over distances corresponding to an attenuation of about 4 or more Neper at a carrier frequency used, said lines substantially comprising aperiodical open-wire lines, 10 selecting said carrier frequencies within a range of about 85 to about 10,000 kilocycles, separating the individual channels by tuned amplifier circuits at the receiver station, and removing local weaknesses in reception, if occurring, by slight 15 alterations of the carrier frequency or by tuning of the receiver.

10. A method of multiple transmission of intelligence of low frequencies up to high frequencies including the television range along communication lines with modulated carrier frequencies forming individual channels over distances corresponding to an attenuation of about 4 or more Neper at a carrier frequency used, said lines substantially comprising aperiodical spaced 25 apart non-concentrical cable lines, selecting said carrier frequencies within a range of about 85 to about 10,000 kilocycles, separating the individual channels by tuned amplifier circuits at the receiver station, and removing local weaknesses 30 in reception, if occurring, by slight alterations of the carrier frequency or by tuning of the receiver.

11. In a method of wired wireless transmission of intelligence of low frequencies up to high frequencies including the television range from point to point employing selective ordinary broadcast receivers at the receiving point; the transmission of modulated carrier waves over aperiodical wires within the high frequency range where the signal level substantially surpasses the noise level and 40 over distances the attenuation of which exceeds about 4 Neper at said carrier frequency.

12. In a method of wired wireless transmission of intelligence of low frequencies up to high frequencies including the television range from point to point employing ordinary selective broadcast receivers at the receiving point, the transmission of waves over aperiodical lines substantially comprising cable wire lines, as ordinarily used for telephone and telegraph communication, in the 50 frequency range of or above 85 kilocycles and over distances the attenuation of which exceeds about 4 Neper at said frequency.

13. In a method of wired wireless transmission of intelligence of low frequencies up to high frequencies including the television range from point to point employing ordinary selective broadcast receivers at the receiving point, the transmission of waves over aperiodical lines substantially comprising open-wire lines, as ordinarily used for telephone and telegraph communication, in the frequency range of or above 85 kilocycles and over distances the attenuation of which exceeds about 4 Neper at said frequency.

14. In a method of wired wireless transmission of intelligence of low frequencies up to high frequencies including the television range from point to point employing tunable selective amplifying receives at the receiving point, the transmission of carrier waves over aperiodical lines substantially comprising cable wire lines, as ordinary used for telephone and telegraph communication, in the frequency range from about 85 kilocycles up to about 10,000 kilocycles, said wired transmission carried over distances the attenuation of which 75

- exceeds about 4 Neper at said carrier frequency.
15. In a method of wired wireless transmission of intelligence of low frequencies up to high frequencies including the television range from point to point employing tunable selective amplifying receivers at the receiving point, the transmission of carrier waves over aperiodical lines substantially comprising open-wire lines, as ordinarily used for telegraph and telephone communication, 10 in the frequency range from about 85 kilocycles up to about 10,000 kilocycles, said wired transmission carried over distances the attenuation of which exceeds about 4 Neper at said carrier frequency.
- 15 16. In a method of wired wireless transmission of intelligence of low frequencies up to high frequencies including the television range from point to point employing selective amplifier circuits at the receiving point: the transmission of 20 modulated carrier waves over lines comprising aperiodical open-wire lines within the high-frequency range above and including about 85 kilocycles and over distances where the attenuation level of said line at the carrier frequency approaches or surpasses the noise level of said line at the carrier frequency.
- 20 17. In a method of wired wireless transmission of intelligence of low frequencies up to high frequencies including the television range from point to point employing selective amplifier circuits at the receiving point: the transmission of modulated carrier waves over lines comprising spaced apart non-concentrical cable lines within the high-frequency range above and including about 25 85 kilocycles and over distances where the attenuation level of said line at the carrier frequency approaches or surpasses the noise level of said line at the carrier frequency.
- 25 18. A system of wired wireless transmission of intelligence of low frequencies up to high frequencies including the television range from point to point comprising a transmitting circuit at one point for modulated carrier waves, a selective amplifier circuit for receiving said carrier waves at another point, said transmitting and said receiving circuits coupled to a line of the type comprising aperiodical non-concentrical conductors, said carrier waves being in the range above and including about 85 kilocycles where the attenuation level of said line at the carrier frequency approaches or surpasses the noise level of said line at the carrier frequency.
- 30 19. A system of wired wireless transmission of intelligence of low frequencies up to high frequencies including the television range from point to point comprising a transmitting circuit at one point for modulated carrier waves in the range of and above 85 kilocycles, a selective amplifier circuit for receiving said carrier waves at another point, said transmitting and said receiving circuits coupled to a line of the type comprising aperiodical non-concentrical conductors, said carrier proceeding from said transmitting circuit to said receiving circuit along said line over a distance causing an attenuation of and exceeding about 4 Neper at said carrier frequency.
- 35 20. A system of wired wireless transmission of intelligence of low frequencies up to high frequencies including the television range from point to point comprising a transmitter at one point for modulated carrier waves within the frequency range from about 85 to about 10,000 kilocycles, a selective ordinary broadcast receiver for said carrier waves at another point, said transmitter and said receiver coupled to a line sub-stantially comprising an aperiodical open-wire line, said carrier proceeding from said transmitter to said receiver along said wire line over a distance causing an attenuation exceeding about 4 Neper at said carrier frequency.
- 40 21. A system of wired wireless transmission of intelligence of low frequencies up to high frequencies including the television range from point to point comprising a transmitter at one point for modulated carrier waves within the frequency range from about 85 to about 10,000 kilocycles, a selective ordinary broadcast receiver for said carrier waves at another point, said transmitter and said receiver coupled to a line substantially comprising an aperiodical non-concentrical spaced apart cable wire line as ordinarily used for telephone or telegraph communication, said carrier proceeding from said transmitter to said receiver along said wire line over a distance causing an attenuation exceeding about 4 Neper at said carrier frequency.
- 45 22. A system of wired wireless transmission of intelligence of low frequencies up to high frequencies including the television range from point to point comprising a transmitting circuit at one point for carrier waves upon which said intelligence is modulated, a selective amplifier circuit for receiving said carrier waves at another point, said transmitting and said receiving circuits coupled to a line of the type comprising aperiodical open-wire lines, said circuits tuned to a carrier high frequency and spaced from each other so that the attenuation level of said line at the carrier frequency approaches or surpasses the noise level of said line at the carrier frequency.
- 50 23. A system of wired wireless transmission of intelligence of low frequencies up to high frequencies including the television range from point to point comprising a transmitting circuit at one point for carrier waves upon which said intelligence is modulated, a selective amplifier circuit for receiving said carrier waves at another point, said transmitting and said receiving circuits coupled to a line of the type comprising aperiodical spaced apart non-concentrical cable lines, said circuits tuned to a carrier high frequency and spaced apart from each other so that the attenuation level of said line at the carrier frequency approaches or surpasses the noise level of said line at the carrier frequency.
- 55 24. A system of wired wireless transmission of intelligence of low frequencies up to high frequencies including the television range from point to point comprising a transmitting circuit at one point for modulated carrier waves, a selective amplifier circuit for receiving said carrier waves at another point, said transmitting and said receiving circuits coupled to a line of the type comprising aperiodical non-concentrical conductors and tuned to a carrier high frequency in the range where the attenuation level of said line at the carrier frequency approaches or surpasses the noise level of said line at the carrier frequency.
- 60 25. A system of wired wireless transmission of intelligence of low frequencies up to high frequencies including the television range from point to point comprising a transmitting circuit at one point for carrier waves upon which said intelligence is modulated, a selective amplifier circuit for receiving said carrier waves at another point, said transmitting and said receiving circuits coupled to a line of the type comprising aperiodical non-concentrical conductors, said circuits tuned to a

carrier high frequency and spaced from each other so that the signal level substantially surpasses the noise level at the carrier frequency.

26. A system of wired wireless transmission of intelligence of low frequencies up to high frequencies including the television range from point to point comprising a transmitting circuit at one point for carrier waves upon which said intelligence is modulated, a selective amplifier circuit for receiving said carrier waves at another point, said transmitting and said receiving circuits coupled to communication lines of the type as ordinarily used for telephone and telegraph communication and comprising aperiodical spaced apart non-concentrical conductors, said transmitting and said receiving circuits tuned to a carrier high frequency and spaced from each other so that the signal level substantially surpasses the noise level.

27. A system of wired wireless transmission of intelligence of low frequencies up to high frequencies including the television range from point to point comprising a transmitting circuit at one point for modulated carrier waves, a selective amplifier circuit for receiving said carrier waves at another point, said transmitting and said receiving circuits coupled to a line of the type comprising aperiodical non-concentrical conductors and tuned to a carrier high frequency in the range where the attenuation level of said line at the carrier frequency approaches or surpasses the noise level of said line at the carrier frequency, the distance of said transmitting and said receiving circuit being such that the attenuation caused by said line amounts to or exceeds about 4 Neper at the carrier frequency.

28. A system of wired wireless transmission of intelligence of low frequencies up to high frequencies including the television range from point to point comprising a transmitting circuit at one point for carrier waves upon which said intelligence is modulated, an ordinary selective broadcast receiver at the other point, said circuit and said receiver coupled to a line substantially of the type as ordinarily used for telephone and telegraph communication and comprising non-concentrical spaced apart conductors, said circuit and said receiver tuned to carrier frequencies exceeding about 85 kilocycles and spaced from each other so that the attenuation caused by said line between said circuit and said receiver equals or exceeds about 4 Neper at a carrier frequency.

29. A system of wired wireless transmission of intelligence of low frequencies up to high frequencies including the television range from point to point comprising a transmitter at one point for modulated carrier waves within the frequency range from about 85 to about 10,000 kilocycles, a selective ordinary broadcast receiver for said carrier waves at another point, said transmitter and said receiver coupled to a line substantially comprising an aperiodical open-wire line as ordinarily used for telephone and telegraph communications, said transmitting circuit and said receiving circuit spaced from each other for a distance causing an attenuation exceeding about 4 Neper at said carrier frequency.

30. A system of wired wireless transmission of intelligence of low frequencies up to high frequencies including the television range from point

to point comprising a transmitter at one point for modulated carrier waves within the frequency range from about 85 to 10,000 kilocycles, a selective ordinary broadcast receiver for said carrier waves at another point, said transmitter and said receiver coupled to a line substantially comprising an aperiodical non-concentrical spaced-apart cable wire line as ordinarily used for telephone or telegraph communication, said transmitter and said receiver spaced from each other for a distance causing an attenuation exceeding about 4 Neper at said carrier frequency.

31. A system of wired wireless transmission of intelligence of low frequencies up to high frequencies including the television range from point to point comprising a transmitting circuit at one point for carrier waves upon which said intelligence is modulated, an ordinary selective broadcast receiver at the other point, said circuit and said receiver coupled to a line comprising aperiodical non-concentrical conductors, said circuit and said receiver tuned to carrier frequencies exceeding about 85 kilocycles and spaced from each other so that the attenuation caused by said line between said circuit and said receiver equals or exceeds about 4 Neper at a carrier frequency.

32. A system of multiple wired wireless transmission of intelligence of low frequencies up to high frequencies including the television range from point to point comprising transmitting circuits at one point for carrier waves upon each of which intelligence is modulated, selective tunable amplifier circuits for receiving said carrier waves at another point, said transmitting and said receiving circuits coupled to a line of the type comprising aperiodical spaced apart non-concentrical conductors, said transmitting circuits capable of transmitting high carrier wave frequencies different from and not interfering with each other, each of said receiving circuits tunable to one of said carrier frequencies thereby separating them from each other, said transmitting and receiving circuits tuned to carrier high frequencies of about and exceeding 85 kilocycles and spaced from each other so that the attenuation caused by the line between said points equals or exceeds about 4 Neper at a carrier frequency.

33. A system as described in claim 32, said line comprising aperiodical open wire lines.

34. A system as described in claim 32, said line comprising aperiodical spaced apart non-concentrical cable lines.

35. A system of wired wireless transmission of intelligence of low frequencies up to high frequencies including the television range from point to point comprising a transmitting circuit at one point for modulated carrier waves in the range of and above about 85 kilocycles, a selective amplifier circuit for receiving said carrier waves at another point, said transmitting and said receiving circuits coupled to a line of the type comprising aperiodical non-concentrical conductors of electrically well conducting material on their outside, said transmitting circuit and said receiving circuit spaced from each other so that the signal level of said line at said carrier frequencies approaches or surpasses the noise level.
